(57) **CLAIM**

The ornamental design for buoyant eyeglass string holder, as shown and described.

DESCRIPTION

FIG. 1 is a perspective view of the buoyant eyeglass string holder of the present invention.

FIG. 2 is a frontal view thereof.

FIG. 3 is a back view thereof.

FIG. 4 is a side view thereof.

FIG. 5 is another side thereof.

FIG. 6 is a top view thereof; and,

FIG. 7 is a bottom view thereof.

The broken lines in the drawings depict environmental subject matter only and form no part of the claimed invention.
